DESIGN FOR A HAT

Florence E. Westmore, North Hollywood, Calif.

Application June 5, 1943, Serial No. 110,369

Term of patent 3½ years

To all whom it may concern:

Be it known that I, Florence E. Westmore, a citizen of the United States, residing in the city of North Hollywood, county of Los Angeles, and State of California, have invented a new, original, and ornamental Design for a Hat, of which the following is a specification, reference being had to the accompanying drawing, forming a part thereof.

Fig. 1 is a side perspective view of a hat showing my new design, and

Fig. 2 is a perspective view of the hat shown in Fig. 1, showing the other side and the top.

Certain parts are shaded by stippling to indicate contrast of color between those parts and the parts that are unstippled.

I claim:

The ornamental design for a hat, as shown and described.

FLORENCE E. WESTMORE.
